(57) **CLAIM**

I claim the ornamental design for a sports helmet, as shown and described.

DESCRIPTION

FIG. 1 is a front, side perspective view of a sports helmet; FIG. 2 is a side view of the sports helmet of FIG. 1; and, FIG. 3 is a front view of the sports helmet of FIG. 1. The dashed/dotted lines depicting boundary lines and the environmental elements shown in broken lines form no part of the claimed design.
